(57) **CLAIM**

The ornamental design for a multi component smoking pipe assembly as shown and described.

DESCRIPTION

FIG. 1 is a top perspective view of a multi component smoking pipe assembly in its fully assembled configuration;

FIG. 2 is a right side view thereof;

FIG. 3 is a left side view thereof;

FIG. 4 is a top view thereof;

FIG. 5 is a bottom view thereof;

FIG. 6 is a back view thereof;

FIG. 7 is a front view thereof;

FIG. 8 is a perspective exploded view thereof;

FIG. 9 is a bottom perspective view of the bowl, shown separately to illustrate aspects of the design not apparent in assembled views;

FIG. 10 is a side view thereof;

FIG. 11 is a bottom view thereof;

FIG. 12 is a top perspective view thereof;

FIG. 13 is a top perspective view of the lid of the bowl, shown separately to illustrate aspects of the design not apparent in assembled views;

FIG. 14 is a perspective view of the pipe body, shown separately to illustrate aspects of the design not apparent in assembled views;

FIG. 15 is a perspective view of the removable sleeve of the pipe body, shown separately to illustrate aspects of the design not apparent in assembled views; and,

FIG. 16 is a perspective view of the poker, shown separately to illustrate aspects of the design not apparent in assembled views.

The broken lines in the drawings depict portions of the multi component smoking pipe assembly that form no part of the claimed design.
